ATTORNEY

UNITED STATES PATENT OFFICE

119,209

DESIGN FOR A MAGNETO ELECTRIC GENERATOR OF BASE MOUNTING TYPE

Edward A. Vogel, Beloit, Wis., assignor to Fairbanks, Morse & Co., Chicago, Ill., a corporation of Illinois

Application April 21, 1939, Serial No. 84,457

Term of patent 14 years

To all whom it may concern:

Be it known that I, Edward A. Vogel, a citizen of the United States, residing in the city of Beloit, county of Rock, State of Wisconsin, have invented a new, original, and ornamental Design for a Magneto Electric Generator of Base Mounting Type, of which the following is a specification, reference being had to the accompanying drawing, forming a part thereof.

In the drawing: Fig. 1 is a top plan view of the magneto electric generator of base mounting type showing my new design; Fig. 2 is a longitudinal side elevation thereof; Fig. 3 is a bottom elevation

of the magneto; Fig. 4 is an end elevation thereof, as viewed from the distributor end of the magneto, and Fig. 5 is an opposite end elevation, viewing the magneto from the impulse coupling end thereof. The side elevation of the magneto, opposite that shown by Fig. 2, corresponds in all important respects to the view of Fig. 2.

I claim:

The ornamental design for a magneto electric generator of base mounting type, substantially as shown and described.

EDWARD A. VOGEL.
